(57) **CLAIM**

The ornamental design for a suction/irrigation handle, as shown and described.

DESCRIPTION

FIG. 1 is a top left side isometric view of a suction/irrigation handle in accordance with the new design;

FIG. 2 is a left side elevation view thereof, a right side elevation view being a mirror image thereof;

FIG. 3 is a top plan view thereof;

FIG. 4 is a bottom plan view thereof;

FIG. 5 is a front elevation view thereof; and,

FIG. 6 is a rear elevation view thereof.

The broken lines immediately adjacent to the shaded areas in FIGS. 3, 5, and 6 represent the bounds of the claimed design, with the lines themselves and the areas within them forming no part of the claimed design.
